UNITED STATES PATENT OFFICE.

ANDREW H. BERNADOU, OF PHILADELPHIA, PENNSYLVANIA, ASSIGNOR OF ONE-HALF
TO HARRY GRASS, OF PHILADELPHIA, PENNSYLVANIA.

RAILWAY-SIGNAL.

1,006,901.

Specification of Letters Patent. Patented Oct. 24, 1911.

Application filed May 26, 1908. Serial No. 435,097.

To all whom it may concern:

Be it known that I, ANDREW H. BERNADOU, a citizen of the United States, residing at Philadelphia, county of Philadelphia, 5 and State of Pennsylvania, have invented a certain new and useful Improvement in Railway-Signals, of which the following is a specification.

My invention relates to a new and useful 10 improvement in railway signals, and has for its object to provide an exceedingly simple and effective device of this character by means of which not only the engineer, but the entire train crew will be notified when a 15 train is two blocks or in the next block ahead of the train in which the signal is given.

Another object of my invention is to provide a signal which may be used with or 20 without the ordinary signals which are used to-day.

A still further object of my invention is to so notify the entire train crew that they will be held responsible if the train of which 25 they have charge passes a blocked section of the road, as in stormy or foggy weather it is not always possible for the engineer when his train is running at a high rate of speed to distinguish whether the signal is indicating danger or that the track is clear ahead and by using my improvement it does away with having to depend upon the sight of the engineer.

Another case of when my improvement 35 would be of great advantage is when an engineer dies or is killed, as is sometimes the case, and the train is proceeding without a guiding hand the rest of the crew will be notified when their train is approaching 40 another one, and when they have noticed that the train does not slack in speed they may stop it themselves thus preventing a wreck or other serious accidents.

With these ends in view this invention 45 consists in the details of construction and combination of elements hereinafter set forth and then specifically designated by the claims.

In order that those skilled in the art to 50 which this invention appertains may understand how to make and use the same I will describe its construction in detail referring

by letter to the accompanying drawing forming a part of this specification, in which—

55

Figure 1 is a diagrammatical view of a section of a track showing my improved signal attached thereto. Fig. 2 a view showing the relation of the brushes to the wheel of the train and connections leading from said 60 brushes to two bells of different tone.

In carrying out my invention as here embodied, A and B represent the two rails of the track which is divided up into the different blocks C, D and E, each block being 65 insulated from the others.

F indicates a battery which supplies the rails with electricity through the medium of the wires G and H.

I indicates short sections of rail or other 70 suitable conductors one of which is placed upon either side of the rail B, one set in each block, and J indicates a similar set of short rails or conductors placed upon either side of the rail A, one set of these also being 75 placed in each block.

The electromagnets K are set in series, supplied with electricity from the battery F through the medium of the wire G, the rail B, the wires L, M and N, the rail A and 80 the wire H. The armatures O are drawn away from the electromagnets K by means of the springs P. These armatures are connected by the wires Q and Q' to the batteries R and S and the battery R is connected with one of these short rails I by wire T, and the other short rail which goes to 85 make up that rail is connected with the contact point U by the wire V. The battery S is connected by a wire W with one of the 90 short rails J, the opposite one of said short rails being connected with the contact point X by the wire Y.

a and b represent two wheels of the train connected by the axle c, and at both sides of 95 the wheels are contact brushes or wheels d, e, f and g secured to the train and in such a manner that they will come in contact with the short rails i and j.

h represents a bell, the posts of which are 100 connected with the contact brushes d and e by the wires i and j. k represents a second bell of different tone than the one indicated by h so that the train crew can readily dis-

tinguish the sound of one from the other. The posts of this bell are connected with the contact brushes *f* and *g* by the wires *l* and *m*.

From the foregoing description it will be seen that should a train enter the block of track indicated by *E* the current of electricity will be short circuited by the wheels *a* and *b*, the axle *c* thus taking current from the electromagnet *K* when the springs *P* will pull the armatures *O* away from the electromagnets *K* and draw them in contact with the contact points *U* and *X* thus partially closing the circuit so that when the brushes *D*, *E*, *F*, and *G* are in contact with the short rail sections a current will pass from the batteries *R* and *S* to the bells *H* and *K* in this way sounding the alarm. From this it will be seen that when a train passes into the block *C*, the contact brushes *f* and *g* will come in contact with the short rails *I* thus sending a current through, and ringing the bell *k*, of which there may be one in the engineer's cab, and one in each car, thus notifying the entire train crew that the train is in the next block but one ahead. And, when this signal is given it would be advisable for the train to slow down. Should the train which is in the block indicated by *A* still be in the block when the following train enters the block indicated by *D*, the contact brushes *d* and *e* coming in contact with the short rails *J* will send a current through the bell *h* thus ringing the same and it being different tone, notifies the entire crew that the train ahead is still in block *E* and that the train in which they have come must be stopped and should the engineer not do so they can open the air valve on any one of the cars, bringing their train to a standstill. But should the bell *k* again ring when they enter the block indicated by *D*, they would know that the train ahead had passed out of the next block. The next succeeding series of circuits would then be closed and the ones just passed would be open, so that a repetition of the above description would occur. Should the signals which are used to-day beside the track such as semaphores be used in conjunction with my improved signal and should these semaphore signals beside the track indicate a clear track ahead after the herein described signal has indicated that the track is not clear the engineer might blow his whistle a number of predetermined times thus notifying the rest of the crew that the track has become clear since the herein described signal has indicated that the track was not clear, and in this way prevent any unnecessary delay because the conductor or other members of the crew would not undertake to apply the safety brakes after the engineer had given his signal.

65 Of course I do not wish to be limited to

the exact details here shown, as in place of one of the bells a buzzer might be used, or in place of the contact brushes some other suitable contact means might be fastened to the train.

Having thus fully described my invention what I claim as new and useful is—

1. In combination with a railway so insulated as to form blocks, a battery connected with the rails of each block, two electromagnets connected in series and with the rails of each block, each block thereby comprising a normally closed track circuit, two pairs of contacts for each block, one pair located on the opposite side of the track from the other, each pair of contacts being connected with a source of energy and with an armature controlled by one of said electromagnets, the armature for one pair of contacts in a block being controlled by an electromagnet in the track circuit of the block next in advance and the armature for the pair of contacts on the opposite side of the track in said block being controlled by an electromagnet in the track circuit of the block two blocks in advance, two pairs of contacts carried by a train for coöperation with said track contacts, two bells of different tone, one pair of said train carried contacts being connected with one bell and the other pair of train carried contacts being connected with the other bell.

2. In combination with a railway so insulated as to form blocks, means for supplying the rails of each block with an electric current, two electromagnets connected in series and with the rails of each block, each block thereby comprising a normally closed track circuit, two pairs of contacts for each block, one pair located on the opposite side of the track from the other, each pair of contacts being connected with a source of energy and with an armature controlled by one of said electromagnets, the armature for one pair of contacts in a block being controlled by an electromagnet in the track circuit of the block next in advance and the armature for the pair of contacts on the opposite side of the track in said block being controlled by an electromagnet in the track circuit of the block two blocks in advance, two pairs of contacts carried by a train for coöperation with said track contacts, two bells of different tone, one pair of said train carried contacts being connected with one bell and the other pair of train carried contacts being connected with the other bell.

3. In combination with a railway so insulated as to form blocks, means for supplying the rails of each block with an electric current, two electromagnets connected in series and with the rails of each block, each block thereby comprising a normally closed track circuit, two pairs of contacts for each

block, one pair located on the opposite side of the track from the other, each pair of contacts being connected with a source of energy and with an armature controlled by 5 one of said electromagnets, the armature for one pair of contacts in a block being controlled by an electromagnet in the track circuit of the block next in advance and the armature for the pair of contacts on the 10 opposite side of the track in said block being controlled by an electromagnet in the track circuit of the block two blocks in ad-

vance, two bells of different tone carried by the train, and means coöperating with the track contacts for putting a predetermined 15 bell in circuit.

In testimony whereof, I have hereunto affixed my signature in the presence of two subscribing witnesses.

ANDREW H. BERNADOU.
